UNITED STATES PATENT OFFICE.

WILLIAM L. COLE, OF MILE END, LONDON, ENGLAND.

APPARATUS FOR APPLYING COATINGS TO BARS, RODS, PIPES, &c.

1,263,858.

Specification of Letters Patent. Patented Apr. 23, 1918.

Application filed December 27, 1917. Serial No. 209,019.

To all whom it may concern:

Be it known that I, WILLIAM LAWES COLE, a subject of the King of Great Britain, and resident of Mile End, in the county 5 of London, England, have invented certain new and useful Improvements in Apparatus for Applying Coatings to Bars, Rods, Pipes, &c., of which the following is a specification.

10 This invention relates to the application of coatings or fluids of various kinds to bars, rods, pipes, ropes or any like articles made in lengths of approximately uniform section.

15 It is the object of this invention to provide for the automatic application of the coatings in such a manner as to avoid waste, or contamination of surrounding objects with the coating material, while insuring 20 that the coating shall be regularly and uniformly applied.

The invention is illustrated in the accompanying drawing in which Figure 1 is a diagrammatic view, and Fig. 2 a sectional view, showing the application of the invention to the coating of rods with materials applied in solution or suspension; Fig. 3 is a diagram illustrating a modification; Fig. 4 is a diagram illustrating a further 30 application of the invention.

Referring to Fig. 1, a tank *a* containing a supply of the fluid such as a varnish or paint, is arranged in a suitable position, and a pipe *b* leading out from near the bottom of the tank communicates with a pump *c* which may for instance be a small rotary pump. This pump delivers the fluid through the pipe *d* to one side of the fitting *e*. If the rod *f* to be coated is a round rod 40 or a tube, the fitting *e* will be tubular and will be arranged as a cross piece as shown in the piping through which the coating fluid passes. The fitting *e* is so formed that the coating material can flow completely around the rod *f* as it passes through the fitting, as seen in Fig. 2. The pipe *g* which carries the coating material away from the said fitting, for example at the bottom thereof, is connected to a small 45 chamber *h*, and through a pipe *i* to a pump *k* which may be similar to the pump *c* but has a higher rate of suction and delivery;

if the pump *k* is identical with the pump *c*, it may be driven at a higher speed for example. The pump *k* delivers the fluid back 55 again through pipe *l* to the upper part of the tank *a*, and any air delivered with the fluid separates therefrom in the tank, which is open at the top to the atmosphere. The bar or rod *f* to be coated is fed through the 60 machine by hand or by any suitable feeding mechanism such as a pair of feed rolls *n*. Suitable feeding devices are known and in use in many existing types of machinery, and need not therefore be illustrated in detail here. The rod *f* approximately fills the 65 apertures at the ends of the transverse fitting *e*, but there is a little clearance around the rod, particularly on the outgoing side as seen in Fig. 2, in order to allow for the 70 additional thickness upon the rod corresponding to the coating. If no steps were taken to prevent the coating material from spouting out around the rod at each side of the fitting, it would inevitably escape in this 75 way, spoiling the regularity of the coating and probably contaminating the machine and everything about it with the coating material. The use of the second pump *k* however, which has a higher rate of suction 80 and delivery than the first pump *c*, insures that there shall be a suction away from the fitting *e* tending to draw away more than the amount of coating material fed thereto. Only outside air can be drawn in to supply 85 this additional quantity, and it is so drawn in at either side as indicated by the arrows in the figures. The result is that only the thin coating desired can be retained on the rod *f* as it passes out of the fitting; the air 90 which is being drawn in sweeps back into the fitting any excess of the material which might tend to adhere to the rod. The air drawn in escapes from the fluid as already stated when it is discharged into the tank 95 *a*, and only fluid is drawn out from the bottom of the tank through the pipe *b*, and delivered to the fitting by the feed pump *c* working at the lower rate of delivery. Either the pipe *b* or the pipe *d* may have 100 a cock in it, as indicated at *m*, which can be used for choking or regulating the rate of flow. The pipes *g*, *i* and *l* may be of larger section than the pipes *b* and *d*, as they will

carry some air as well as the coating fluid, but this is not essential, as the fluid can travel faster through the one part of the circuit than the other. The chamber *h* is 5 principally useful in starting up the apparatus, when the pump *c* commences to deliver the fluid before the pump *k* has created a sufficient suction in the pipe *i* to draw in air and to prevent the fluid from spouting out at the ends of the fitting *e*. The chamber *h* then serves to receive and collect the fluid for a few moments until the pump *k* has created the necessary suction.

The invention is suitable for use in applying any coating material to wires, rods, tubes and so forth which can be fed through the machine in lengths, or to laths or moldings of wood and the like of any section which can conveniently be passed through 10 a transverse correspondingly shaped slot in a fitting *e* arranged in a line of piping.

It will be apparent that the essential feature of the invention is the continuous supply of the coating material or fluid to the fitting through which the article to be coated passes, and the continuous withdrawal of the fluid at the other side of the said fitting by some device tending to draw out more of the coating material or fluid than can 15 reach it, so that there is a reduced pressure inside the fitting causing some air to be drawn in and carried away with the fluid. Any other convenient arrangement equivalent to that of Fig. 1 may be used to attain 20 this result. For example, Fig. 3 indicates 25 diagrammatically an arrangement wherein only one pump *k* is used, the tank *a* being arranged in an elevated position so that the supply of fluid to the fitting *e* takes place 30 by gravity, controlled by a cock *m*. The pump *k* thus serves to supply the whole 35 energy required by pumping up the fluid to the elevated tank *a*, on the one hand, and drawing out fluid and air from the fitting *e* 40 on the other hand.

The coated rod as it passes out from the fitting or cross piece *e*, may pass through a drying apparatus of a known type, indicated diagrammatically at *o*, in which it is 45 dried by heating, and any finely disintegrated material may be dusted on the rod before drying if such material is to be incorporated with the coating.

If a powder is to be applied, it may 50 conveniently be dealt with by a similar appliance to that above referred to. Such an apparatus is indicated in Fig. 4, combined with an apparatus as in Fig. 1 for applying 55 a fluid coating to the rod. The apparatus 60 at the left hand side in Fig. 4 is the same as is shown in Fig. 1, and is lettered to correspond with that figure. The rod *f*, after leaving the fitting *e*, passes on through another fitting *s* in which a dusting material or powder is applied to it. This ma-

terial is contained in a vessel *p*, and is stirred up to form a dust cloud therein by means of beaters *q* on a shaft driven from any suitable source of power, not shown. The dust cloud, containing the particles of 70 dust mixed with or carried in suspension in air, is drawn out by means of a fan *r*, which corresponds in its function with the slower pump *c*, in delivering the stream of dust-laden air to the fitting *s* through the pipes 75 as shown. A second fan *t*, which runs faster than fan *r* or is otherwise arranged to draw more air than is delivered by fan *r*, draws off the stream of air from fitting *s*, and also draws in some air around the rod *f* where 80 it passes into and out of the said fitting, so that none of the dust can escape except that which is securely applied to and adheres to the coating on rod *f*. The fan *t* delivers the stream of air through the pipes back 85 to the vessel *p*, where the excess air drawn in at the fitting *s* escapes through a screen of gauze *u* of fine mesh, fine enough to prevent escape of the particles of dust in suspension in the air in said vessel. 90

Fig. 4 also shows plain feed rolls *z* used in place of the grooved feed rolls *n* of Fig. 1, the rolls *z* being set at an angle to the axis of the rod *f*, so that they twist the rod *f* as they feed it forward, as indicated 95 by the arrows. They may be covered with india-rubber or other resilient material in order to grip the rod effectively for feeding purposes.

Further, in Fig. 4 is illustrated the application of a wrapped coating such as a tape *v* to the rod. This is applied from reels *w* carried on a revoluble head *x*, the tapes or the like being wrapped around the coated rod *f* in this case after the dusting material has been applied thereto in fitting *s*. Obviously the tapes might be applied directly to the rod by the same mechanism directly after it leaves the fitting *e* in Fig. 1. 100

It will be obvious that many modifications may be made in the design and construction or arrangement of the mechanism hereinbefore described, without departing from the scope of the invention. 110

Wherever the term "coating" is used in 115 this specification, it includes of course impregnating or treating with fluids for any suitable purpose and it depends on the nature of the article treated and the fluid applied, whether the latter remains on the surface as a true coating, or soaks into the article, or reacts therewith chemically or otherwise. 120

Having thus described my invention and the manner in which it is to be performed, 125 I declare that what I claim is:—

1. Apparatus for applying a coating to an article such as a bar, rod, tube and so forth, said apparatus comprising a hollow fitting having apertures therein through which the 130

article may pass longitudinally with some clearance, a vessel adapted to contain the coating material, and a circulating system including said vessel and said fitting, and 5 including also means for circulating the coating material around the said system, said circulating means being designed to draw in air around the article being coated, at the apertures of the said fitting, as well 10 as to draw away excess of the coating material from said fitting.

2. Apparatus for applying a coating material to an article such as a bar, rod, tube and so forth, said apparatus comprising a 15 hollow fitting with apertures therein through which the article is adapted to pass longitudinally with some clearance, feeding means for supplying the coating material to the interior of said fitting, and suction 20 means for drawing out the coating material from said fitting, said suction means being adapted to draw fluid from the fitting at a faster rate than that at which the coating material is supplied by the feeding means, 25 whereby also air is drawn in around the article at the apertures of the fitting.

3. Apparatus for applying a coating material to an article such as a bar, rod, tube and so forth, said apparatus comprising a 30 fitting with apertures therein through which the article is adapted to pass longitudinally with some clearance, a vessel for containing the coating material, means for supplying the coating material from said vessel and for 35 delivering it to the interior of the said fitting, a pipe leading out from said fitting back to the said vessel, and suction feeding means in said pipe adapted to draw fluid out of said fitting at a faster rate than that 40 at which the coating material is supplied thereto, and thus to draw in air around the article at the apertures of the fitting, whereby the said suction feeding means is enabled to return the residual coating material 45 which has not adhered to the article back to the vessel together with any air drawn in at the apertures of the fitting.

4. Apparatus for applying a coating material to an article such as a bar, rod, tube and so forth, said apparatus comprising a 50 hollow fitting with apertures therein through which the article is adapted to pass longitudinally with some clearance, a vessel for containing the coating material, a pipe leading from said vessel to said fitting, a pump in said pipe, another pipe leading back from said fitting to said vessel, and a pump in said second pipe, said second mentioned pump having a higher rate of delivery than 55 said first mentioned pump, whereby air is caused to be drawn in at the apertures of the fitting around the article to which the coating material is applied.

5. Apparatus for applying a coating to an 60 article such as a bar, rod, tube and so forth,

said apparatus comprising a hollow fitting having apertures therein through which the article may pass longitudinally with some clearance, a mechanism for feeding the article through the said fitting during the coating operation, a vessel adapted to contain the coating material, and a circulating system including said vessel and said fitting, and including also means for circulating the coating material around the said system, said 70 circulating means being designed to draw in air around the article being coated, at the apertures of the said fitting, as well as to draw away excess of the coating material from said fitting.

6. Apparatus for applying a coating to an article such as a bar, rod, tube and so forth, said apparatus comprising a hollow fitting having apertures therein through which the article may pass longitudinally 80 with some clearance, a set of feed rolls disposed at an angle such that they will feed the article through the said fitting while also turning it on its axis as it passes therethrough, a vessel adapted to contain the 85 coating material, and a circulating system including said vessel and said fitting, and including also means for circulating the coating material around the said system, said circulating means being designed to 90 draw in air around the article being coated, at the apertures of the said fitting, as well as to draw away excess of the coating material from said fitting.

7. In combination, two sets of apparatus 100 for applying coatings to an article such as a bar, rod, tube and so forth, the first said apparatus being adapted to apply a fluid coating to said article, and the second said apparatus comprising a hollow fitting 105 through which the article is passed after leaving the first said set of apparatus, means for supplying a dusting material in suspension to said fitting, and means for drawing out a current of air from said fitting at a 110 faster rate than that at which the suspension of dusting material is supplied thereto, whereby also some air is drawn in at the apertures of the fitting through which the article passes.

8. Apparatus for applying coating materials to an article such as a bar, rod, tube and so forth, said apparatus comprising a vessel for containing a fluid coating material, a vessel for containing a pulverulent coating 120 material, means for making a dust cloud or suspension of said pulverulent material, separate hollow fittings through apertures in which the article to be coated may pass successively, means for circulating the fluid coating material through the first said fitting, said circulating means being of such a character as to draw away excess of the coating material from said first fitting while 125 drawing in air at apertures of said fitting,

and means for circulating the suspension of pulverulent material through the second said fitting, said circulating means for the suspension of pulverulent material being also of such a character as to draw in air at apertures of said second fitting, as well as drawing away from the said fitting any excess

of said suspension with any particles of the pulverulent material which have not adhered to the coating material applied to the 10 surface of the article in the first mentioned fitting.

WILLIAM L. COLE.
